GAS FIRED OVEN OR KILN

Filed May 17, 1921

2 Sheets-Sheet 2

Fig. 3.

Inventor:
John Henry Marlow
By Shankshawman
Atty:

UNITED STATES PATENT OFFICE.

JOHN HENRY MARLOW, OF STOKE-UPON-TRENT, ENGLAND.

GAS-FIRED OVEN OR KILN.

Application filed May 17, 1921. Serial No. 470,265.

To all whom it may concern:

Be it known that I, JOHN HENRY MARLOW, subject of the King of Great Britain and Ireland, and resident of Stoke-upon-Trent, in the county of Stafford, England, manager, has invented certain new and useful Improvements in or Applicable to Gas-Fired Ovens or Kilns, (for which I have made application for patent in Great Britain, numbered 22,641, dated the 30th of July, 1920), of which the following is a specification.

My invention relates to improvements in or applicable to gas-fired ovens or kilns for use in the manufacture of tiles, pottery and other ware and for other purposes, the object being improved means for conveying and controlling the gas and air so as to greatly increase the intensity of the heat in the oven to effect the ware therein and to economize in the use of fuel.

My invention will be fully described with reference to the accompanying drawings in which,

Fig. 1 is a sectional plan of a portion of a tunnel oven constructed in accordance with my invention,

Fig. 2 is a sectional elevation through line Y—Y of same,

Fig. 3 is a transverse section through line Z—Z of Fig. 1, and

Fig. 4 is a portion of Fig. 3 slightly modified to be herein referred to.

In these figures U is a tunnel oven, V the interior thereof and W the carrier or travelling vehicle for conveying the ware to be treated, these parts being of the usual well known construction.

In accordance with my said invention the gas is conveyed from the usual gas producer into channels *a* arranged at each side of the oven, the gas passing through an opening *b* which is controlled by a damper *c* and then into the combustion chambers 1 which is located beyond the main vertical walls R of the oven, as shown. The necessary supply of air to be mixed with the gas passes through a series of pipes *d* arranged longitudinally from the outlet end X of the oven, but in some cases such pipes *d* may extend

through the side walls of the oven as will be understood. The air conveyed by the pipes *d* enters chambers *e* and after passing through an outlet *f* in the wall thereof it meets the incoming gas in the chamber 1 where combustion takes place and the flame is produced. The flame from the combustion chamber 1 passes through openings *g* in the wall thereof and into a second combustion chamber 2 being then conducted towards the inlet or front end of the oven by way of a passage *h* which is of irregular depth, or stepped as shown to diminish toward the front to interrupt or control the passage of the gas so as to equalize the supply thereof to the orifices, pipes or burners *p* thereby preventing the rush of gas to the far end of the passage *h* or to the farthest pipe or burner *p*. The said orifices, pipes, or burners *p* may be of varying diameters, the largest opening or bore of the pipes being nearest to the combustion chamber 2, as shown in the drawings. Sometimes it may be an advantage to employ pipes or burners of irregular or varying heights.

The air issuing through pipes *d* is dampered or cut off when the temperature of the heat in the oven rises to a predetermined degree and an independent supply of hot air is introduced through the ends *j* of the pipes *j* into the chamber *k*, through an opening *m* and into the chamber 2 where it meets the incoming gas passing from the chamber 1, through opening *g*, combustion then taking place in the second combustion chamber 2. The said pipes *j* extend longitudinally of the oven and are built on or supported by baffles *o* to expose a great portion of the surfaces of the pipe *j* to the flame projected through the pipes or orifices *p*, the air passing therethrough being superheated or raised to a very great intensity prior to its entry into the chamber *k*, from which chamber the air passes into chamber 2 where combustion takes place, the flame produces therein travelling through passage *h* to the burners *p* and into the interior of the oven to treat the ware passing therethrough on the carrier W. The walls of the chambers *k* extend upward to join

the inner arch, or they may be covered by a plate or top wall.

As will be seen from the sectional plan at Fig. 1 two gas supply channels *a*, one at each side of the oven, are employed to supply gas to either of the two combustion chambers 1 and 2 and to the pipes or burners arranged at each side of the oven. Combustion only takes place in combustion chamber 1 whilst air is being admitted through the pipes *d*, the combustion in chamber 2 taking place when the superheated air from the pipes *j* passes from chamber *k* and meets the gas immediately it has passed from chamber 1 and into the combustion chamber 2. The said pipes *j* extended longitudinally in a direction away from the inlet end *S* of the oven but if desired the pipes may pass through the side walls of the oven and then extend longitudinally in close proximity to the burners.

The air pipes *d* are shown in dotted lines at Fig. 3 for convenience to locate their height only but the outlet ends of such air pipes are some distance in front of the combustion chambers 2 as will be clearly seen from Figs. 1 and 2.

At Fig. 4 is illustrated a section of a small portion of the interior of the oven slightly modified. The open spaces between the baffles *o* (Fig. 2) are covered with slabs *n* of refractory material to enclose the air pipes *j* and burners *p* and thereby muffle the flame from the orifices, pipes or burners *p* preventing the products of combustion or the flame coming into direct contact with the ware being passed through the oven.

As before stated two gas supply channels are arranged at each side of the oven but both channels may communicate with one gas conduit leading from one gas producer, or if desired two separate gas producers may be employed as will be understood.

The cold air inlet pipes *d* supply cold air to the gas as initially supplied to the burner, and this supply of air may be cut out or reduced, when desired, and when the furnace or kiln has been initially heated, a part of the heat caused by a mixture of gas and cold air, passes along to a combustion chamber designated as the second combustion chamber. The cold air serves to form a gas and air mixture which is not as economical as a mixture of hot air with the same character of fuel gas. The air being heated is rarefied to a greater degree than the cold air, and the combustion is more perfect and automatic. In starting the kiln, the use of dampers is essential, whereas with heated air they are not required.

What I claim as my invention and desire to secure by Letters Patent is:—

1. A tunnel oven or kiln provided on opposite sides with combustion chambers and air supply pipes, passages communicating

with the combustion chambers, said passages decreasing in area towards the front of the oven or kiln, and a series of orifices which communicate with said passages.

2. A tunnel oven or kiln having chambers and means for the admission of air and fuel gas thereto, other combustion chambers into which the mixed air and gas is passed from the first combustion chambers, means communicating with the second combustion chambers for supplying heated air thereto, and a forwardly diminishing passage provided at intervals with flame exit openings.

3. A kiln for the purpose set forth, consisting of a structure having a tunnel with longitudinal side ledges, combustion chambers and passages therefrom located below the plane of the ledges, vents through the ledges which communicate with the passages, pipes maintained within the tunnel for supplying heated air to combustion chambers, and supports for the pipes that extend from the ledges of the tunnel upward to provide baffles.

4. A tunnel kiln which structurally provides on each side of the tunnel flues which are connected with a fuel gas supply, chambers to which air is supplied, dampers controlling a supply of gas and air to said chambers, other combustion chambers in communication with the aforesaid mentioned chambers, air supply pipes maintained within the tunnel of the kiln to supply heated air to combustion chambers, stepped passages which communicate with the combustion chambers, and spaced openings through the upper walls of said passages.

5. Means for mixing air and gas for fuel in kilns, comprising channels and chambers into which air and gas are admitted, dampers for limiting the supply of gas to the chambers, combustion chambers in communication with the initial chambers into which cold air is admitted, pipes maintained within the tunnel of the kiln for supplying heated air to chambers in the rear of the last mentioned chambers, passages communicating with the aforesaid chambers, said passages diminishing in area toward the front, and a plurality of spaced openings through which the flames pass to the interior of the kiln, substantially as shown.

6. A tunnel kiln for the purpose set forth, having side ledges and truckways below the plane of said ledges, pipes maintained above the ledges and adjacent to the inner side walls of the tunnel, said pipes terminating within a chamber, a plurality of connected chambers, the rear chambers having air inlet pipes, chambers into which fuel gas is admitted under a damper control, said chambers communicating with the chambers which receive cold air, chambers having openings, means for supplying heated air

to the last mentioned chambers, and combustion chambers which communicate with longitudinal passages having openings which communicate with the interior of the 5 tunnel and are located adjacent to the side walls thereof and in proximity to the hot air supply pipes.

In testimony whereof I have heretunto set my hand in the presence of two witnesses.

JOHN HENRY MARLOW.
